Inventor

Henry B. Adams

United States Patent Office.

HENRY B. ADAMS, OF NEW YORK, N. Y.

Letters Patent No. 97,751, dated December 14, 1869.

IMPROVEMENT IN FLUTING-MACHINES.

The Schedule referred to in these Letters Patent and making part of the same.

To all whom it may concern:

Be it known that I, HENRY B. ADAMS, of the city, county, and State of New York, have made certain new and useful Improvements in Machines for Goffering and Fluting; and I do hereby declare that the following is a full, clear, and exact description of the construction and operation of the same, reference being had to the accompanying drawings, making part of this specification, in which—

Figure 1 is a front elevation of the machine with my improvements.

Figure 2, a central vertical cross-section of the same.

Figure 3, a detached top view of the lever, which presses the under roller, shown on a reduced scale.

Similar letters of reference indicate corresponding parts in the several figures.

The nature of the invention consists in providing the lever, in which the lower roller of the machine rests, with means for adjusting its pressure with great convenience, and to operate in a ready manner with accuracy.

To enable others skilled in the art to make and use my improvements, I will proceed to describe its construction and operation in detail.

A represents the upper, and B the lower roller, which are constructed in the usual manner, hollow, for heating, and on their periphery with the desired corrugations or ribs, as used for goffering.

C represents the bed-plate of the machine, and D is the side frame of the same, which is secured to the bed-plate, extends rearward, and extends over along the top of the upper roller, as shown, in order to support and guide said top roller.

The lower roller is guided and rests and turns in a two-armed lever, E, which has its fulcrum in the rear part of the frame D.

The fulcrum bearing of said lever is constructed with two pointed set-screws, f f, entering in the side of the lever.

One of these set-screws f f is fixed in the rear of the frame D, the other in a part, G, cast on the bed-plate C.

The forward end of said lever is forked and provided with bearings, H H, in which the lower lever is supported; and one of the forked ends is formed with a

projecting handle, I, and also with the eye J on the same, to which the treadle of the machine is attached by means of a cord, K.

The rear end of said lever has a central projection downward, and to it is hinged a short vertical double-armed lever, L, which has its long arm projecting down near the bed-plate, and to it is attached a spiral spring, M, which has its other end secured to the forward part of the bed-plate.

The short arm of said lever L bears against a set-screw, N, fitted in the rear part of the lever E, by means of which the relative position of the lever E, is regulated, and in that manner the spring obliged to stretch more or less, or its tension and action upon said lever and roller regulated.

The upper roller has one bearing in the side frame, and passes through it, and has an ordinary hand-crank attached to its outer end.

The other end of said roller is supported in a small movable bearing-piece, O, which is secured to the top portion of the frame by means of a thumb-screw P, in order to provide for changing said roller with others of different patterns.

Q represents an ordinary clamp, for securing the machine to the table.

The cord K has a loop, R, on its end, through which I pass a secondary loop; and I employ a small metal ring, S, through said loop, to prevent it from withdrawing from the loop R. By this means the said cord can be lengthened or shortened conveniently, and in a more ready and less expensive manner than with a belt and buckle, as now commonly employed.

It will be evident from the foregoing that the machine, as herein described, is more convenient, can be regulated more accurately, and is more durable than those before known or used.

Having fully described my invention, What I claim, and desire to secure by Letters Patent, is—

The spring M, levers E and L, the set-screw N, and roller B, when combined and arranged to operate substantially as and for the purpose herein shown.

HENRY B. ADAMS.
